UNITED STATES PATENT OFFICE

ROBERT LESLIE CHILES, OF KNOXVILLE, TENNESSEE

DETECTOR-TUBE CIRCUIT

Application filed September 1, 1928. Serial No. 303,499.

- This invention relates to improvements in radio receiving sets, the general object of the invention being to provide means whereby two or more detector tubes can be used in the 5 set so as to secure a smoother tone and increased volume, while decreasing fading, as what one tube fails to pick up, the other (or others) is likely to find, one tube acting without interfering with the other.
- 10 This invention also consists in certain other features of construction and in the combination and arrangement of the several parts, to be hereinafter fully described, illustrated in the accompanying drawing and 15 specifically pointed out in the appended claim.

In describing the invention in detail, reference will be had to the accompanying drawing, which is a diagrammatic view of the invention.

The drawing shows two detector tubes T , though, of course, it will be understood that more than two tubes can be used, if desired, and the negative binding posts of these tubes 25 are connected by a conductor 1 with the negative side of the "A" battery B and the positive posts of the tubes are connected by a conductor 2 with the positive side of the battery.

30 The coil C is connected by the conductors 3 with the grid binding posts of the tubes and a separate grid condenser and grid leak 4 is placed in the line adjacent each tube.

The plate posts of the tubes are connected 35 by the conductors 5 with the plate binding post of the amplifying transformer 6 and a .00025 condenser 7 is connected by the conductors 8 with the line 1 and the line 5.

40 When more than two detector tubes are used, these other tubes are connected with the second tube T by the conductors 9 which are shown in dotted lines in the drawing.

45 Thus it will be seen that the positive terminals of the tubes are connected with the negative side of the source, with the grid posts of the tubes connected in multiple with the coil, with a separate grid condenser and grid leak for each grid binding post. The plate binding posts of the tubes are connected 50 in multiple with the plate binding

posts of the amplifying device, with the condenser connected with the plate circuit and the negative line for the tube filaments ahead of the supply.

As before stated, this arrangement will produce smoother tones, with increased volume, while decreasing fading, as what one detector tube fails to pick up, the others are likely to find, and each tube will put what it detects into the audio side without interfering with the other tube.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A radio receiving set comprising a number of detector tubes, means for connecting the filaments of the tubes with a source of supply, means for connecting the grid posts of the tubes with a coil, a grid condenser and leak arranged in the circuit between each grid post and coil, means for connecting the plate posts of the tubes with a transformer and a condenser connected with the plate post circuit and with the negative filament circuit.

In testimony whereof I affix my signature.

ROBERT LESLIE CHILES.
